CONTAINER

John M. Hothersall, Brooklyn, N. Y., assignor to
 American Can Company, New York, N. Y., a
 corporation of New Jersey

Application April 28, 1938, Serial No. 204,899

1 Claim. (Cl. 229—5.5)

The present invention relates to containers for the packaging and delivery of liquids, such as milk, fruit juices or the like and has particular reference to a sanitary fibre container of a construction which will readily shed water from its top end.

The invention constitutes an improvement upon the container illustrated and described in my United States Patent 2,085,979, issued July 6, 1937, and is especially an improvement on the top closure construction thereof.

The invention contemplates a container top member which is secured to the body of the container by an interfolding of marginal portions of the top and the body members in an end seam, the top member being domed so that its outer or upper surface is above the plane of the surrounding end seam folds or joints.

An object of the invention, therefore, is the provision of a sanitary fibre container for milk and other beverages wherein the top closure member is formed so that water or other foreign matter is prevented from collecting on the top of the container thus preventing contamination of the surfaces thereof.

Another object is the provision of such a container wherein the top closure member is provided with a panel which is raised above the end seam connecting the closure member with its body so that water falling on the container top will readily run off over the end seam.

Numerous other objects and advantages of the invention will be apparent as it is better understood from the following description, which, taken in connection with the accompanying drawing, discloses a preferred embodiment thereof.

Referring to the drawing:

Figure 1 is a perspective view of a container embodying the instant invention and illustrating the same in a closed and sealed condition;

Fig. 2 is an enlarged composite section taken through the container substantially along a composite plane indicated by the lines 2—2 in Fig. 1; and

Fig. 3 is an enlarged top plan view of the top closure member of the container before it is assembled with the container body, the view showing the closure element of the member in open position.

As a preferred embodiment of the invention the drawing shows a container of the general construction described in detail in my patent hereinbefore mentioned. The container briefly comprises a substantially rectangular body 11 closed at its ends with top and bottom closure

members 12, 13. The body 11 is preferably formed from a single sheet of fibrous material folded at right angles to provide four side walls 15 and having the short edges of the sheet overlapped to form a vertical lap side seam 16. The seam edges are preferably secured with a suitable adhesive so that a liquid tight side seam results.

The top and bottom closure members 12, 13 are preferably squares of fibre material which are interlocked with the adjacent end or marginal portions of the body. For this purpose the body marginal portions are bent obliquely inwardly as at 18 and thence outwardly as at 19 thereby providing ledges 21 against which the closure members are supported. The extreme edges of the body marginal portions are bent outwardly and thence inwardly over the outer edges of the closure members thus providing opposite end flanges 22 which hold the members in place.

The bent parts 19, 22 of the body adjacent its ends and the edges of the top and bottom closure members 12, 13 are preferably secured with a suitable liquid proof adhesive. This manner of construction provides a liquid tight end seam 25 which is generally indicated by the numeral 25.

The bottom closure member 13 is preferably flat throughout as best shown in Fig. 2. In contrast to this the top closure member 12 is formed with a raised or domed panel 27 which is struck outwardly from the material of the member. The area of the panel preferably extends over the entire area of the container top inside the inner edge of the top end seam flange 22. In other words the domed panel fits tightly against the edge of the top end seam. It also extends above the plane of the end seam and practically merges into the end seam in a curved panel section or reenforcing shoulder 28. This construction of top closure prevents collection of water, such as rain water, ice water, or any other foreign matter on the top of the container, any such material immediately running off over the end seam 25 so that the top will be left clean.

The top closure member 12 is also provided with a dispensing opening 31 which is formed in the raised panel 27 adjacent one corner of the container top. This opening is preferably closed with a hinged closure element 32 which is similar to that shown in my patent hereinbefore mentioned. The closure element is secured to the top by a staple 33. A portion of the closure element on one side of the staple extends over the dispensing opening 31 and is formed with a struck out plug section 34 which fits tightly into the opening when the container

is closed. This portion of the closure element extends over an area surrounding the dispensing opening and also extends over the adjacent portion of the end seam so that foreign matter is prevented from collecting on and contaminating these portions of the container. The portion of the closure element on the opposite side of the staple serves as a tab (marked 35) for lifting or carrying the container and this tab is provided with a hole 36 which may be used in hanging the container onto a hook or the like if desired.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

A container comprising a tubular fibre body having an end portion thereof inclined inwardly and thence outwardly to provide a substantially flat end supporting ledge, and an end closure member including a substantially flat peripheral portion engaging and supported by said ledge, the inner portion of said closure member comprising a domed central panel disposed above the plane of said ledge and terminating at its outer periphery in a downwardly extending reinforcing shoulder merging into said flat ledge, the terminal portion of said body outwardly of said ledge being folded inwardly and downwardly over said closure to constitute a substantially flat flange secured to the closure in a liquid-proof seam, the inner extremity of said flange abutting closely against the outer shouldered periphery of said domed central panel, whereby liquid foreign matter falling on the closure member will readily run off over the seam.

JOHN M. HOTHERSALL.
